COMBINED SUCTION CLEANING AND FLOOR POLISHING APPARATUS

Gordon Thomas Fillery, Johannesburg, Transvaal, Union of South Africa, and Edward Patterson, North Hillington, England; said Patterson assignor to said Fillery

Application September 28, 1950, Serial No. 187,248

Claims priority, application Great Britain November 4, 1949

4 Claims. (Cl. 15—328)

This invention relates to combined suction-cleaning and floor-polishing apparatus of the kind comprising a casing formed integral with or carrying a suction nozzle, a rotary floor polishing element or elements carried by the casing for retraction from the on-the-floor or operative position into the casing, and an electric motor carried by the casing which drives the polishing element or elements.

In apparatus according to the invention, the polishing element, when in the on-the-floor or operative position, supports the nozzle in the off-the-floor position, and means are provided whereby retraction of the polishing element renders inoperative the drive thereto and lowers the body portion and nozzle towards floor level.

It will be understood that the expressions "on-the-floor" and "off-the-floor" as herein employed in connection with the nozzle refer respectively to the operative and inoperative positions of the nozzle which, in the "on-the-floor" position may either be in actual contact with the floor surface or may be slightly raised therefrom.

The invention may be carried into practice in various ways but one embodiment is shown, by way of example, in the accompanying drawings, in which:

Figure 1 shows the apparatus in side elevation with part of the casing cut away and the polishing brushes in the retracted position,

Figure 2 is a bottom plan of Figure 1,

Figure 3 is a view similar to that of Figure 1 of the rear portion of the apparatus, but on a larger scale and with the polishing brushes in their on-the-floor position,

Figure 4 shows the retracting mechanism in section on the line IV—IV of Figure 3,

Figure 5 is a section on the line V—V of Figure 3, and

Figure 6 shows the complete apparatus in perspective. In the construction shown in the drawings, the apparatus comprises a body portion or hood A of metal which constitutes the casing of the apparatus as a whole. Formed integrally with an internal wall C¹ within the casing A are the walls C⁴ of a nozzle duct B containing a rotary agitator B¹ and furnished with a curved cover plate B². The duct B is in open communication with a casing C² for a fan C driven by the spindle D¹ of an electric motor D mounted in the upper part of the casing A. The spindle D¹ extends through the eye of the fan in the wall C¹, across the narrower end of the duct B, and emerges at B³ through a tubular bearing extension of the cover plate B². The fan casing C² is provided with a delivery conduit C³ having a coupling C⁵ for cooperation with a coupling E¹ at the lower end of the dust bag E. The spindle D¹ carries a pulley D² which is coupled by an elastic belt D³ to the agitator B¹. The spindle D¹ is thus disposed vertically so as to intersect the fore-and-aft axis X—X of the casing A, the spindle carrying a boss D⁴ covered with material having a high coefficient of friction, such for example as hard rubber. The forward end A¹ of the casing A may be provided with a recess or cowl A² for a head-light A³.

That end of the casing A remote from the nozzle B and hereinafter referred to, for convenience only, as the "rear" end A⁴ of the casing, is provided with a single central floor contacting wheel F, two similar supporting wheels F¹F² being provided within the casing A and on

2

opposite sides thereof immediately abaft the opening B⁴ of the nozzle B. Thus, when the there floor-contacting wheels F, F¹, F² are in the on-the-floor position (Figure 1), the whole weight of the apparatus is supported thereby and the nozzle B⁴ is in the on floor position required for suction cleaning purposes, the brushes B⁵ of the agitator sweeping the surface Z of the floor, or the carpet thereon, when the motor D is set in operation. Centrally disposed within the rear part A⁴ of the cas-

10 ing A is a guide comprising two mutually parallel and laterally spaced channel members G secured to the casing A by side plates G¹ (Figure 4), the members G constituting part of a holder for the purpose described below. The two channel members G of the holder lie 15 equidistant from, and on opposite sides respectively of, the central fore-and-aft plane containing the vertical axis of the driving spindle D¹, that is to say the vertical plane containing the axis X—X of the apparatus, the two channels G being, however, inclined downwardly, 20 as shown in Figures 1 and 3, at an angle of, say 45° to the said fore-and-aft longitudinal axis X—X. Mounted to pivot on a pin H¹ journalled in bosses H² carried by the side plates G¹ is a bell-crank lever the first arm H³ of which extends freely through a slot H⁴ on the rear wall A⁴ of the casing A and is notched, slotted or forked at H⁵ to cooperate with a latch J loaded by a spring J² and pivotally mounted at J³ on a fork J⁴ constituting part of a cross piece G² interconnecting the side plates G¹. The first arm H³ of the bell-crank lever is connected through a biassing spring H⁶ to a fixed anchorage pin H⁷ interconnecting the side plates G¹. The other or second arm H⁸ of the bell-crank lever extends through a slot K¹ in a slide member K, the arm H⁸ being bifurcated to engage a pin K² extending across the slot K¹ 35 in the slide member K. The slide member K is formed integrally with a carrier L for two polishing brushes L¹, L². The opposite longitudinal margins of the slide member K respectively engage the two parallel channel members G of the guide or holder within which the slide member K is thus movable, the common longitudinal axis W—W of the interengaging slide member K and guide being therefore inclined, as shown in Figure 1, to the vertical axis V—V of the driving spindle D¹ and to the central fore-and-aft axis X—X of the apparatus.

40 The carrier L is in the form of an elongated metallic bar or bridge-piece, with the inclined slide member K formed integral therewith and the said common axis W—W of the slide member K and guide G, G transverse to the length of the bar at a part approximately midway in the length of the bar. Equidistant from the common axis W—W of the slide member and guide, and on opposite sides thereof respectively on the bridge piece L, are the bearings L³ for the two rotary brushes L¹, L² each of which comprises an upper cup-like part L⁴ cooperating with the rubber-covered driving boss D⁴ on the driving spindle D¹, an intermediate part or brush body L⁵ of reduced diameter and a lower portion constituted by the bristles L⁶, the brush body L⁵ and the bristles L⁶ being detachable as a unit from the upper cup-like part L⁴ by releasing a central retaining screw L⁷.

45 As will be clear from Figures 1 and 3, the rear portion A⁴ of the casing A is inset at M, with the inner wall of this recess provided with a slot at H⁴ through which the guides G, the arm H³ of the bell-crank lever and the latch J project. When the apparatus is to be used solely as a suction cleaner the spring-loaded latch J, which lies accessible in the recess M, is manually tripped and the bell-crank lever H³, H⁸ is turned into the position shown in Figure 1 to move the carrier upwards. This movement of the lever H³, H⁸ will, of course, be assisted by the upward force on the brushes due to the weight of the apparatus. As the first arm H³ of the lever passes beyond a dead-center position, continued movement of the lever in the same direction is effected by the biassing spring H⁶ until the carrier L and brushes L¹, L² reach their uppermost or retracted position wherein they are held by the biassing spring H⁶. By reason of the central inclined guide G, G, this retracting movement not only causes the brushes L¹, L² to rise from the floor surface Z—Z but, at the

same time, moves the driving rims L^4 of the brushes out of operative engagement with the driving member or boss D^4 on the spindle D^1 . The whole weight of the apparatus is now taken by the three floor-contacting wheels F^1, F^2 as shown in Figure 1, the nozzle B^4 being in its operative position on or adjacent to the floor surface $Z-Z$ so that dust, and particles loosened by the rotating agitator B^1 , are drawn up through the nozzle attachment B , and through the eye of the fan to the filter bag E . The load on the motor D is now represented only by the drive to the fan C and to the agitator B^1 .

If now it is desired to use the apparatus as a floor polisher, the first arm H^3 of the bell-crank lever, lying accessible in the recess M at the rear end of the casing A , is manually turned upwards against the action of the loading spring H^6 so that the slide member K , and therefore the carrier L and brushes L^1, L^2 are moved downwards towards the floor $Z-Z$. This downward movement of the brushes may be facilitated by the operator wholly or partially taking the weight of the apparatus while turning the bell-crank lever H^3, H^8 . As the first arm H^3 of the bell-crank lever passes beyond the dead-center referred to above, continued movement of the lever in the same direction will be assisted by the biassing spring H^6 . By reason of the inclined central guide G, G , as the carrier L moves downwards the driving rims L^4 of the brushes also move towards the driving boss D^4 on the spindle D^1 . As the brushes L^1, L^2 reach their on-the-floor position (Figure 3), the driving rims L^4 of the brushes engage the driving boss D^4 on the spindle D^1 and the spring-loaded latch J snaps over the notched or forked end H^5 of the bell-crank lever H^3, H^8 . The latch J thus holds the brushes L^1, L^2 in their on-the-floor position, with the casing A , nozzle B^4 and floor wheels F, F^1, F^2 raised from floor level $Z-Z$.

Reconversion of the apparatus for suction cleaning purposes merely requires tripping of the latch J whereupon the upward force on the brushes L^1, L^2 will effect the initial retraction of the brushes and carrier L until the bell-crank lever passes the dead-center whereupon the retraction will be completed with the assistance of the biassing spring H^6 acting through the bell-crank lever H^3, H^8 on the slide member K .

It will be apparent that by centrally guiding the carrier L in accordance with the invention, risk of jamming due to tilting or canting of the carrier and brushes will be reduced to a minimum whilst operation and latching of the carrier and brushes can be effected centrally. Further, with the rotary polishing elements driven simultaneously by a central driving member or spindle, the drive will be substantially equally distributed to the two polishing elements due to the central guide, and to the forces of retraction and restoration of the carrier and polishing elements being approximately in alignment with the axis of rotation of the driving spindle.

If desired, the slide member may be carried by the body portion of the apparatus whilst the guide or channel members are formed integral with or mounted on the carrier. Further, by connecting the handle N of

the apparatus through a hoop or fork N^1 to pivots N^2 on opposite sides of the casing A , the apparatus can be propelled with either the floor polishing elements or the nozzle leading. The boss D^4 on the driving spindle D^1 , instead of being right-cylindrical as shown, may be in the form of a truncated cone, with or without similar inclination of the driving rims L^4 on the polishing elements.

What we claim as our invention and desire to secure by Letters Patent is:

1. Combined suction cleaning and floor polishing apparatus comprising a casing, a motor carried by said casing, a driving spindle driven by said motor, suction means driven by said motor, fixed guide means carried by said casing and inclined both to the floor and to the axis of said driving spindle, a floor polishing assembly comprising a carrier element slidably mounted on said guide means and a floor polishing element rotatably mounted on said carrier and having an exterior driving rim, and means for moving said carrier along said guide means and retaining it in position thereon at both ends of its movement, said guide means being so positioned relative to said spindle and to the floor that movement of said polishing assembly into a position at the lower end of said guide means brings said driving rim into frictional driving contact with said spindle and said floor polishing element into working contact with the floor, in which position said polishing assembly supports said casing and suction means away from the floor, whereas upward movement of said polishing assembly slides it angularly away from the driving spindle and floor and thereby permits the casing and suction means to sink to an operative position with respect to said floor.

2. Apparatus as claimed in claim 1 in which the carrier moving and retaining means includes means for positively locking said polishing assembly in floor engaging position.

3. Apparatus as claimed in claim 1 in which said carrier element carries a second floor polishing element, said floor polishing elements being rotatable about vertical axes lying on opposite sides of and equidistant from said spindle.

4. Apparatus as claimed in claim 1 in which the carrier moving and retaining means comprises a bell crank lever pivotally mounted on said casing, means connecting said bell crank lever to said carrier so that swinging of said lever in one direction past a dead center position urges said polishing assembly towards the floor, whereas movement of said lever in the opposite direction urges said polishing assembly away from the floor, and a spring connected to said casing and to said lever which acts to yieldably retain said lever on either side of its dead center position.
